UNITED STATES PATENT OFFICE.

FRANK B. HALL, JR., OF NEW YORK, N. Y.

DESIGN FOR A WALL-LIGHT CASING.

Application filed December 5, 1927. Serial No. 24,393. Term of patent 3½ years.

To all whom it may concern:

Be it known that I, FRANK B. HALL, Jr., a citizen of the United States, residing at 435 East 57th Street, city, county, and State of New York, U. S. A., have invented a new, original, and ornamental Design for a Wall-Light Casing, of which the following is a specification, reference being had to the accompanying drawing, forming part thereof.

Figure 1 is a front elevation of the casing.

Figure 2 is a side elevation of the casing, the manner of mounting the casing being shown by dotted construction lines.

Figure 3 is a plan view of the casing.

I claim:

The ornamental design for a wall-light casing, as shown.
